CLAIM

The ornamental design for a trim pen as shown and described.

DESCRIPTION

FIG. 1 is a top perspective view of a first embodiment of a new trim pen design;

FIG. 2 is a bottom perspective view of a first embodiment of a new trim pen design;

FIG. 3 is a front view of the trim pen of FIGS. 1 and 2;

FIG. 4 is a back view of the trim pen of FIGS. 1 and 2;

FIG. 5 is a right side view of the trim pen of FIGS. 1 and 2;

FIG. 6 is a left side view of the trim pen of FIGS. 1 and 2;

FIG. 7 is a top view of the trim pen of FIGS. 1 and 2;

FIG. 8 is a bottom view of the trim pen of FIGS. 1 and 2;

FIG. 9 is a top perspective view of a second embodiment of a new trim pen design;

FIG. 10 is a bottom perspective view of a second embodiment of a new trim pen design;

FIG. 11 is a front view of the trim pen of FIGS. 9 and 10;

FIG. 12 is a back view of the trim pen of FIGS. 9 and 10;

FIG. 13 is a right side view of the trim pen of FIGS. 9 and 10;

FIG. 14 is a left side view of the trim pen of FIGS. 9 and 10;

FIG. 15 is a top view of the trim pen of FIGS. 9 and 10; and,

FIG. 16 is a bottom view of the trim pen of FIGS. 9 and 10.

The broken lines in the Figures show portions of the trim pen which form no part of the claimed design, but are shown for environment and background.
